United States Patent Office

Des. 175,309
Patented Aug. 9, 1955

175,309

GIRDLE

Ethel R. Kaupp, New York, N. Y.

Application March 31, 1955, Serial No. 35,298

Term of patent 3½ years

(Cl. D20—2)

Fig. 1 is a front elevational view of a girdle showing my new design.

Fig. 2 is a rear elevational view.

I claim:

The ornamental design for a girdle, substantially as shown.
